SCOOP

Raymond Linsky, Coatesville, Pa., assignor to
Welded Steel Shapes, Inc., Coatesville, Pa.

Application July 29, 1946, Serial No. 686,972

1 Claim. (Cl. 37—140)

1

This invention relates to earth working implements.

An object of this invention is to provide a device in the form of a digger or scraper, which is designed to scrape and collect the dirt or other material, and which can be adjusted so as to pick up either a partial or full load.

Another object of this invention is to provide a device of this kind which includes improved latching means for latching the scoop in either scraping position or in dragging position.

A further object of this invention is to provide a device of this kind having a renewable scraping blade and runners on the bottom so as to protect the bottom against undue wear.

A still further object of this invention is to provide a rotatable scraper which when towed behind a tractor or other suitable towing means may be selectively used as a digger, scraper, or spreader and as a carrier of a load and when pushed may be used as a bulldozer.

Yet a further object of this invention is to provide a rotary scraper of this kind having selective control means for fixing the scraper in rotated position and independent control means for selectively adjusting the angle of the cutting blade with respect to the earth.

Still another object of this invention is to provide means for an operator to selectively control the position of the rotatable scraper and the position of the cutting blade with respect to the earth during operation of the scraper.

With the above and other objects in view, my invention consists in the arrangement, combination and details of construction disclosed in the drawings and specification, and then more particularly pointed out in the appended claim.

In the drawings,

Wherein similar reference characters designate similar parts throughout the respective views,

Figure 1 is a top plan view of a scoop constructed according to an embodiment of my invention,

Figure 2 is a front elevation partly broken away,

Figure 3 is a section, partly broken away, taken on the line 3—3 of Figure 1,

Figure 4 is an end elevation, partly broken away, and partly in section,

Figure 5 is a side elevation,

Figure 6 is a side elevation showing the scoop in a rotated position,

Figure 7 is a bottom view, partly broken away.

Referring to the drawing, the numeral 15 designates generally a drawbar assembly which is

2

adapted for attaching a rotatable scoop 16 behind a tractor or other suitable machine for towing and/or pushing the scoop 16. The drawbar assembly 15 has secured to its forward end an attachment plate 17 by which the drawbar 15 is attached to the tractor by means of a shackle 18.

The plate 17 is formed at its front end with a plurality of vertically spaced apart openings 19 to any one of which the shackle 18 may be attached for initially adjusting the drawbar to a desired angular position relative to the tractor and the earth. The drawbar 15 is formed with a pair of rearwardly divergent arms 20 and a connecting bar 21 between the ends of the arms 20. Extending rearwardly from the divergent ends of each arm 20 and the bar 21 there is attached a drawbar connecting plate 22. The plates 22 are each formed with a segmental arcuate opening 24 near the rear end into which the scoop 16 is adapted to be engaged.

The scoop 16 is formed of an open sided or partial cylinder having a bottom surface 25. A cutting blade 26 is secured below the surface 25 by bolts 27 or other suitable fastening means and skid plates 28 are fixed to the bottom 25 behind the blade 26 to prevent injury to the bottom of the scoop 16. Also fixed to the ends of the scoop 16 are skids 29 about part of the open side of the cylinder to prevent damage to the edges of the ends of the cylinder. Trunnions 30 fixed to the end walls of the scoop 16 extend outwardly therefrom and are adapted to engage in the arcuate slot 24 of the drawbar connecting plate 22.

Fixed to each end wall of the scoop 16 are stop bars 31, 32 and 34 which extend therefrom and are formed with a straight edge on one side and a beveled edge on the opposite side. The stop bars 31 and 32 are used to hold the scoop 16 in position for digging and spreading respectively, while the bar 34 is used to hold the scoop 16 in position for unloading, bulldozing or travelling empty. Since the stops 31 and 32 are used in dragging the scoop 16 and stop 34 is sometimes used in pushing the scoop 16, the beveled edge of stop 34 is reversed from that of stops 31 and 32 in order that the straight edge of stop bar 34 will properly engage the lower face of plate 44 for bulldozing.

For holding the scoop 16 in selected rotated position there is provided a locking or trip lever assembly which is carried by the drawbar and engages the scoop 16 through stops 31, 32, and 34. This locking assembly consists of a pair of trip lever supporting plates 35, one on each side of the cylinder 16. The support plates 35 are

formed of a triangular plate having a pair of obtusely related edges. The plate 35 is pivotally mounted on the drawbar connecting plate 22 by a pivot pin 36 at the obtuse angle, the plate 35 providing a lever having a rearwardly extending arm 37 and a vertical arm 38. The rear end of the arm 37, between the drawbar plate 22 and scoop 16, is formed with a bearing in which the trunnion 30 is rotatably engaged.

A trip lever rod 39 is loosely engaged in the upper end of the arms 38 and extends across the front of the scoop 16. Fixed to the trip lever rod 39 and extending upwardly therefrom is a trip lever 40, which is supported on the rod 39 by struts 41. Also fixed to the rod 39 by welding or other suitable means, at each end is a lock lever 42 which extends rearwardly from the rod 39, and having a short forward extension 43.

A lock plate 44 is fixed to the rear end of the lever 42 and extends approximately perpendicular thereto and is adapted to be engaged by the stops 31, 32, and 34. A spring 45 between the plate 44 and the rear end of the lever 37 constantly pulls the lock plate 44 rearwardly into locked position. A stop 46 fixed to each plate 35 engages the upper side of the lever arm 43 to limit the rearward movement of the lever 42.

A second control lever 47 is pivotally carried by the cross car 21 of the drawbar 15 by a pair of ears 48, fixed on the bar 21. The lever 47 is formed of an L-shaped member having a rearwardly extending arm 49. A link 50 connects the rear end of the arm 49 to the trip lever rod 39. The rear end of the link 50 is fixed to a sleeve or bearing 51 rotatable on the rod 39. A stop member 52 is fixed on the upper end of each of the ears 48 and is engageable with the lever arm 49 to limit the upper swinging of the arm 49 and the toggle action of the link 50. The control lever 47, or partial load lever, is used to control the angle of the cutting blade 26 by raising or lowering the front end of the scoop 16 when the scoop 16 is locked against rotation.

In the use and operation of this assembly, when the trip lever 40 is pulled forward, as by a rope 52 in the hands of an operator, as the tractor moves, the scoop 16 is free to rotate. To use as a digger, the lever 40 is pulled forward and the scoop 16 allowed to rotate until the stop 31 approaches the lock plate 44, at which time the lever 40 is permitted to be pulled rearwardly by springs 45, and the lock plate 44 engages the forward edge of the stop 31 preventing further rotation. As the scoop 16 becomes filled with material, the weight of the material, acting through the linkage arrangement of plates 35 and 22, rotates the scoop 16 against the dragging force and moves the blade 26 to non-digging or slightly raised position.

For spreading material from the scoop 16, the filled scoop 16 is permitted to rotate until the stop 32 is engaged with the lock plate 44 at which time the blade 26 is partly behind the scoop 16 and the open side is dragging on the ground, thus permitting material to be spread on the ground.

For unloading the scoop 16, the scoop 16 is permitted to rotate until the beveled side of stop 34 is engageable with the rear side of plate 44, at which time the open side of the scoop 16 is rearward, permitting the material to freely fall from the scoop 16.

Pushing or bulldozing may be accomplished by allowing the scoop 16 to rotate until the stop 34 has passed the lock plate 44, then the lock plate 44 is dropped into place so that the straight edge of the stop 34 engages the lower or forward side of the lock plate 44 and the scoop may then be pushed rearwardly.

When it is desired to carry a partially filled

15 scoop 16, with the scoop in digging position, the partial load lever 47 is pulled forwardly by a rope 52a by the operator, thus raising the rod 39 by means of link 50 and pivoting the plate 35 about its pivot 36, rotating the scoop 16 so the 20 blade 26 is raised above the earth. To lock the scoop 16 in this position, it is necessary only to pull the lever 47 forwardly until the pivot 53 between the arm 49 and link 50 is above a straight line between the rod 39 and fulcrum 54 of lever 25 47. To release the scoop 16 from this load carrying position, the lever 47 is let free and the lever 40 moved forwardly until the L-shaped bar 55, fixed on the lever 40 engages the link 50 to move the pivot 53 below the line between bar 39 and the 30 fulcrum 54.

I do not mean to confine myself to the exact details of construction herein disclosed, but claim all variations falling within the purview of the appended claim.

35 What I claim is—

In combination a rotatable scoop, a drawbar for said scoop and means for selectively positioning said scoop relative to said drawbar, said drawbar including a pair of rearwardly extending connecting plates, each of said plates formed with a segmental arcuate opening, a trip lever supporting plate pivotally secured to said connecting plates, trunnions on said scoop rotatable in said supporting plates and engageable in said 45 arcuate openings, a trip lever rod pivotally secured between said supporting plates, a trip lever fixed to said rod, spring pressed locking members fixed to said rod, and stop or locking 50 bars on said scoop engageable with said locking members, a second lever pivotally mounted on said drawbar, and a link loosely connected to said rod and said second lever for pivoting said supporting plate relative to said drawbar.

RAYMOND LINSKY.
